UNITED STATES PATENT OFFICE.

CHARLES F. STACKPOLE, OF LYNN, MASSACHUSETTS.

EDGE-BURNISHING MACHINE.

1,288,250.

Specification of Letters Patent. Patented Dec. 17, 1918.

Application filed April 6, 1916. Serial No. 89,872.

To all whom it may concern:

Be it known that I, CHARLES F. STACKPOLE, a citizen of the United States, and resident of Lynn, County of Essex, Commonwealth of Massachusetts, have invented an Improvement in Edge-Burnishing Machines, of which the following description, in connection with the accompanying drawings, is a specification, like characters on the drawings representing like parts in each of the several views.

This invention relates to mechanisms equipped with reciprocating or vibrating tools for burnishing, or compacting and smoothing, surfaces and edges of work. More particularly the invention has to do with a mechanism of this type specially designed and adapted for use in burnishing the edges of the soles of boots and shoes, commonly known in the trade as "edge setters". The function of this type of device being to condense and smooth the edges of the shoe sole by a rapid succession of relatively minute rubbing or sliding strokes of the operating tool or "iron", it is important for rapid and effective work that the operating tool be vibrated or reciprocated at a very high rate of speed. Since the tool is usually operated by a crank or eccentric connection to a rotating driving shaft, it results that when run at this high speed there is a constant minute hammering or jarring in the bearings of the connections which transmit the reciprocations to the tool so that with even the looseness in these bearings necessary for free operation there is a tendency to press out or extrude the oil from the bearings so that they become dry in a relatively short time and also wear at a relatively high rate. It is requisite in a mechanism of this type to provide a yielding element in the mounting of the operating tool so that it can yield upward or backward to some small extent as the work is pressed against the tool or "iron" by the operator, and as heretofore customarily constructed this yielding element has added considerably to the weight of the vibrated or reciprocated element carrying the tool so that a relatively large and heavy mass of metal with a correspondingly great momentum has had to be moved with the rapid vibrations of the tool.

A prime object of the present invention is to provide a mounting for the holder or carrier of an edge setter or burnishing tool wherein provision is made for the requisites

resilient yielding upward or backward of the iron or tool by the use of a yielding element which permits a resilient yield of the pivotal mounting for the tool carrier so that neither said resilient element itself or the parts auxiliary thereto are mounted on the vibrating arm or carrier of the tool but are stationary so that the swinging tool arm or carrier can be made relatively light and of small momentum. In accordance with my invention provision is also made for easily and quickly adjusting the tension of this resilient element, if desired, without stopping or interfering with the operation of the tool. In accordance with my invention means is provided whereby the vibrating arm carrying the edge setter tool may be connected to be moved positively from its operating shaft in both directions and equipped with a resilient device adapted to hold the shafts or pivots in the connections constantly at one side of the bearings therefor thus preventing any minute pounding or jarring in these bearings. The invention will be better understood from the following detailed description taken in connection with the accompanying drawings and will be thereafter pointed out in the appended claims.

85

Referring to the drawings:

Figure 1 is a front view of a machine attachment embodying my invention;

Fig. 2 is a side elevation thereof, one side of a double or twin machine being broken away as the two sides are identical; and

Fig. 3 is a view partly in elevation and partly in section on line 3-3 of Fig. 1, with certain elements removed.

A suitable base or pedestal 10 is provided with an upright 11 at its top in which is journaled a horizontal shaft 12. The machine is preferably, though not necessarily, made as a double or "twin" type in which case the shaft 12 would be extended through another upright at the right of that shown in Fig. 2 with a set of devices the duplicate of that to be described, but such duplicate construction being of no special importance in the present case it is not herein shown, the second upright being broken away as indicated at 11'. The shaft 12 is driven by any suitable means such as a belt pulley 13 and has fixed on its outer end a crank pin or eccentric 14 to which is fitted one end of a link 15, the other end of which is pivotally connected at 16 to the top of a swinging tool

carrier arm 17 that has an intermediate horizontally extended sleeve 18 fitted for bearing on a pivot pin 19. The pivot pin 19 is fixed to an arm 20, being shown as clamped 5 thereto by a nut 21. The arm 20 has at its inner end an extended bearing sleeve 22 fitted to turn on a pivot pin 23 horizontally set into the base column as indicated at 24. The outer end of the arm 20 is projected out to 10 some little distance beyond the pivot 19 where it is formed with an enlarged head 25, having a passage therethrough for a rod 26 that is pivoted to a bracket 27 at the top of the upright 11 as indicated at 27' and depends therefrom. The head 25 is shown as 15 provided with rounded lugs 28 extending crosswise of the face thereof and fitting correspondingly concaved recesses in a presser block 29 slidably fitted on the rod 26 and 20 acted on by a coil spring 30 also mounted on said rod and reacting against an adjustable nut 31 threaded on the upper portion of said rod. The extent to which the head 25 and hence the arm 20 may be depressed by the 25 spring 30 is limited by a stop nut 32 adjustably threaded on the lower end of the rod 26; the nuts 31 and 32 having suitable lock nuts 33, 34, respectively, associated therewith as is usual. Thus it will be understood 30 that the spring 30 will normally hold the arm 20 and hence the tool carrying arm 17 35 yieldingly pressed downward as far as permitted by the adjustment of the nut 32 and with a tension determined by the adjustment of the nut 31. The tool carrying arm 17 can thus be made relatively light since it does not have to carry the spring 30 or the mountings and backings therefor, the operative effect of said spring being transmitted to the 40 tool carrying arm through the pivot pin 19 as will be readily understood. Thus the weight and consequent momentum of the principal vibrating part, *i. e.*, the tool carrying arm 17 is largely reduced. To further 45 reduce and minimize the injurious effects heretofore due to the pounding and jarring due to the momentum of this tool carrier, I provide means whereby the pivot and shaft connections for operating this 50 arm are kept from minute pounding or jarring in their bearings. For this purpose I mount a stout coil spring 35 having a backing and support at one end against a down-turned ledge 36 which may be formed in one 55 with the bracket 27 and pressing at its other end against a block 37 adjustable transversely in the upper portion of the arm 17 by means of a follower screw pin 38. Thus by setting up the screw pin 38 to the requisite 60 extent the spring 35 may be placed under the necessary degree of tension to hold the bearing in the link 15 for the pin 14 constantly pressed against the left side of said pin as shown, and likewise keeping the bearing pin 16 constantly pressed against the

right hand side of its bearing in the link 15 as shown in Fig. 1. In this way any working or jarring of these pins in their bearings is prevented and the same action also of course obtains in the bearing of the sleeve 18 on the pivot pin 19. The bracket 27 and its depending extension 36 is preferably, in case the machine is made double, formed as a bar extending across from one tool arm to the other at the other side of the machine as 70 partly indicated in Fig. 2. The working tool or "iron" is indicated at 39 yieldingly held in the lower end of the tool carrier arm 17 as is usual by suitable means shown as a detent spring 40. It will be understood that 75 the present construction with a single operating tool or iron is adapted for use by cobblers and in repair shops. For shoe factory uses the carrier arm 17 will ordinarily be provided with a forked lower end 80 equipped with two irons as is usual, and as shown for example in my earlier Patent No. 1,041,692 patented October 15, 1912. It will be understood that the described upward or backward resilient yield of the tool carrier 85 arm which will ordinarily be within limits of about one-eighth of an inch is especially useful when operating on thin, light work, and that the tension of the spring will be correspondingly increased for heavier grades 90 of work.

With the described construction, the size and weight, and consequent momentum of the vibrating parts, is reduced to a minimum since only the tool carrier arm 17 itself and 100 the tool with the connecting link from the driving shaft are moved and hence the tendency to jarring or minute pounding in the working bearings is minimized. The importance of this in connection with the further provision for spring pressing the pivot pins to one side of their bearings will be appreciated when it is considered that the usual operating speed of these tools is about three thousand reciprocations per minute or upward. By virtue of the present improved 105 features of construction I am enabled to largely increase the usual operating speed of the tool with consequently increased capacity for work. I am aware that the invention may be embodied in other specific forms 110 without departing from the spirit or essential attributes thereof, and I therefore desire the present embodiment to be considered as illustrative and not restrictive, reference 115 being had to the appended claims rather than to the foregoing description to indicate the scope of the invention.

Having described my invention, what I claim as new and desire to secure by Letters 125 Patent is:

1. Edge burnishing mechanism, comprising a tool carrier mounted for reciprocation and equipped with an operating tool, means having operating connections to said car- 130

rier for imparting small amplitude reciprocations thereto, and means extraneous of said tool carrier and of said connections for causing coöperative elements of the bearings 5 thereof to be pressed constantly to each other yieldingly at the same side thereof.

2. Edge burnishing mechanism, comprising a tool carrier formed as a swingingly mounted arm equipped with an operating 10 tool, a driving shaft having an eccentric and link connection to said arm for operating the same, and a spring pressing upon said arm to cause the bearings of said link connection to be pressed yieldingly against each other 15 constantly on the same side whereby jarring or minute pounding in said bearings is eliminated.

3. Edge burnishing mechanism, comprising a tool carrier formed as a swingingly mounted arm equipped with an operating 20 tool, a driving shaft having an eccentric and link connection to said arm for operating the same, the spring having a fixed backing and pressing upon said arm to cause

the bearings of said link connection to be 25 pressed yieldingly against each other constantly on the same side whereby jarring or minute pounding in said bearings is eliminated, and means for adjusting the tension of said spring. 30

4. Edge burnishing mechanism, comprising a tool carrier formed as a swingingly mounted arm equipped with an operating tool, a driving shaft to operate said carrier having pivoted operating connections there- 35 to, means for yieldingly holding coöperative portions of said pivotal connections constantly pressed together at one side thereof in operation, and means extraneous of said tool carrier arm for yieldingly holding it 40 and the tool carried thereby at a normal forward limit of movement and with a capability of limited yielding backward under pressure of the work as it is operated on.

In testimony whereof, I have signed my 45 name to this specification.

CHARLES F. STACKPOLE.
